(57) **CLAIM**

We claim the ornamental design for an enclosure for a
blender assembly, as shown and described.

DESCRIPTION

FIG. 1 is a front perspective view of an enclosure for a
blender assembly of the present disclosure;

FIG. 2 is a rear perspective view of the enclosure for a
blender assembly of FIG. 1;

FIG. 3 is a front elevational view of the enclosure for a
blender assembly of FIG. 1;

FIG. 4 is a rear elevational view of the enclosure for a
blender assembly of FIG. 1;

FIG. 5 is a first side elevational view of the enclosure for a
blender assembly of FIG. 1;

FIG. 6 is a second side elevational view of the enclosure for a
blender assembly of FIG. 1;

FIG. 7 is a top plan view of the enclosure for a blender
assembly of FIG. 1;

FIG. 8 is a bottom plan view of the enclosure for a blender
assembly of FIG. 1; and,

FIG. 9 is a front top perspective view of an enclosure for a
blender assembly, where the enclosure portion has been
moved to a raised position.

The broken lines depict portions of the article that form no
part of the claimed design.
